(57) **CLAIM**

The ornamental design for a kite, as shown.

DESCRIPTION

FIG. 1 is an isometric view from the front and above of the new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The portion of the kite shown in dashed lines is for environment only, and forms no part of the claimed design.
